DESIGN FOR A SELF-CONTAINED AIR CONDITIONER CABINET

Herbert F. Weissinger, Detroit, Mich.

Application June 19, 1937, Serial No. 69,925

Term of patent 3½ years

To all whom it may concern:

Be it known that I, Herbert F. Weissinger, a citizen of United States of America, and resident of the city of Detroit, in the county of Wayne and State of Michigan, have invented a new, original, and ornamental Design for a Self-Contained Air Conditioner Cabinet, of which the following is a specification, reference being had to the accompanying drawing forming part thereof.

Fig. 1 is a top plan view of a self-contained air conditioner cabinet showing my new design;

Fig. 2 is a front view; and

Fig. 3 is an end view thereof.

I claim:

The ornamental design for a self-contained air conditioner cabinet, as shown.

HERBERT F. WEISSINGER.
